UNITED STATES PATENT OFFICE

CHARLES C. HOWARD, OF LOUISVILLE, KENTUCKY

FOLDING MECHANISM

Original application filed November 22, 1928, Serial No. 321,216. Divided and this application filed September 20, 1929. Serial No. 394,007.

This application is a division of an application filed by me November 22, 1928, Serial No. 321,216.

I have heretofore produced a book in which the several leaves have been formed with tongues along their binding edges, the tongues of alternate leaves being relatively staggered so that the application of adhesive to the free ends of the tongues will cause the tongues on alternate leaves to be secured together, relative transverse shifting of the leaves being prevented by the tongues on one leaf passing through the spaces or notches between the tongues on an adjacent leaf.

The present invention provides means whereby the leaves will be received from the cutting mechanism, the free ends of the tongues folded on themselves, and the leaves then delivered to means for applying adhesive to the tongues, the alinement of the sheets or leaves being maintained at all stages. It must be understood, however, that while the present invention is designed primarily as a part of the book-making machine disclosed in my aforesaid application, its usefulness is not limited to that particular machine and it may be employed to hold sheets having their ends free of tongues. The invention is illustrated in the accompanying drawings and resides in certain novel features which will be hereinafter first fully described and then more particularly defined in the appended claims.

In the drawings:

Figure 1 is a side elevation of a machine having the present invention embodied therein,

Figure 2 is a detail elevation of a portion of the side of the machine, opposite the side seen in Figure 1, and more particularly showing the operating gearing,

Figure 3 is a longitudinal section,

Figure 4 is a plan view of the chute,

Figure 5 is a section on the line 5—5 of Figure 4,

Figure 6 is a transverse section, showing the folding devices in elevation,

Figure 7 is a section on the line 7—7 of Figure 6,

Figure 8 is a view similar to Figure 7, showing the parts in a different position,

Figure 9 is a somewhat enlarged detail of a part of the mechanism shown in Figures 7 and 8,

Figure 10 is a detail view showing sheets before folding,

Figure 11 is a similar view showing sheets after folding.

In the operation of a machine embodying the present invention, the sheets or leaves of paper are carried over a feed table 4 to cutters 5 by the action of which notches are cut in their advancing or forward ends to produce tongues, the tongues upon successive sheets being relatively staggered. A motor 7 drives all the working elements.

From the cutters, the sheets pass forwardly into a chute consisting of an inclined table 82 carried by frame members 84 and having its upper end arranged immediately adjacent a pair of feed rollers 85 and 86 which are located immediately at the rear of the cutting devices, as shown in Figure 1, the roller 85 being a hard surface positively driven roller and the upper roller 86 being a presser roller having a more or less resilient working surface and resting by gravity upon the roller 85. The advancing edge of the sheet with the tongues cut thereon passes directly from the cutting table to the bight of the rollers 85 and 86 and will, of course, be gripped thereby and fed into the chute, and preferably the upper presser roller will be in alined sections provided with rather narrow peripheries while the lower roller will be continuous and extend across the entire width of the machine. Guard fingers 87 are provided at the rear of the feed rollers and extend longitudinally above the chute so that the leaves or sheets will be prevented from flying over the chute and will be turned down into the same, it being understood that, in actual operation, the action is so rapid that the sheets pass from the cutting mechanism at very high speed and are apt to fly some distance beyond the feed rollers after leaving the latter. The guards 87 are preferably leaf springs secured at their lower ends to brackets 88 and having their upper ends supported by a cross rod 89 secured in any approved manner to the main frame, the brackets 88

55

100

being secured on an angle bar 90 which extends across the main frame above and in advance of the bight-forming elements of the folding mechanism. At the lower end 5 of the table 82 is a slotted cross bar 91 over which the cut end edge of the sheet comes to rest, a transverse stop bar 92 being arranged adjacent the lower edge of the slotted bar 91 in the path of the sheet, as shown in Figure 7. Depending from the cross bar 91 and the frame bars 84 are guide plates 93 each having a groove 94 in its inner face. Immediately over and spaced from the slotted bar 91 and secured upon the frame bars in any 10 convenient manner is a guiding shield 95 which is curved upwardly and serves as a deflector so that if a sheet advancing to the folding mechanism should tend to rise from the table 82 it will be turned back onto the same 15 by this deflector. Carried by bearings in brackets 96 secured on the frame bars 84 are rollers 97 which have slight longitudinal corrugations in their peripheries and are so disposed that the bight defined by them will be 20 aligned with the slot 98 in the cross bar 91, and it is to be noted that the rear edge of the deflector 95 is disposed in a plane slightly in 25 advance of a plane passing through the slot 98 and between the rollers 97. Slidably 30 mounted in the grooves 94 in the guide plates 93 is a head plate 99 and a folder blade 100, the folder blade having a reinforcing plate 101 secured to its lower end portion whereby buckling of the blade is prevented, and the 35 blade and said plate being secured to the head plate 99 by set bolts 102 inserted through vertically extending slots 103 in the blade and the plate 101, as shown clearly in Figure 7. This construction permits the blade to be 40 adjusted to compensate for wear and also to attain the desired throw of the blade in the holding operation. Secured to the lower edge of the head plate 99 is a bracket or a plurality of brackets 104 which have lips 105 45 projecting under the lower edges of the blade and the reinforcing plate 101, and in each said lip is mounted a set screw 106 bearing against the lower edge of the reinforcing plate and facilitating its adjustment in an 50 obvious manner. The upper end or the working edge of the blade is intended to be within the slot 98 when the blade is in its lowest position so that it will be in position to immediately engage a sheet or sheets extending 55 over the slot. The stop bar 92 has a bracket 107 secured on its upper side and projecting forwardly therefrom to align with the rear wall of the slot 98, and at the front edge of 60 said bracket is an upstanding lip 108 which passes into the space between the rollers 97 and is beveled so that it may fit close to the adjacent roller. Guide pins or rods 109 depend from the stop bar 92 at or near the ends 65 thereof and pass through guide lugs 110 projecting from the head plate 99, and secured

to said guide pins 109, adjacent the upper ends thereof, are brackets 111 to which are pivoted the upper ends of links 112, the lower ends of said links being pivoted to the rear ends of levers 113 which are fulcrumed between their ends upon brackets or fulcrum blocks 114 secured to the lower corners of the guide plates 93, the forward ends of said levers projecting under the head plate 99 and reinforcing plate 101. Abutment screws 115 70 are fitted through the free ends of the levers 113 to be engaged by the head plate 99 or the reinforcing plate 101 when the folder blade is lowered, and springs 116 extend between and are attached to the fulcrum of the respective lever 113 and the bracket 111 so that the springs tend by their contraction to lower the stop bar 92 and the bracket 107 carried thereby. Upon referring to Figures 7 and 8, it will be understood that, when the folder blade is lowered, the levers 113 will be 75 rocked so that the stop bar 92 will be raised and will be interposed in the path of a sheet advancing over the table 82 and the cross bar 91. As the upward movement of the folder blade occurs, the springs 116 will draw the stop bar 92 downwardly so that the projecting portion of the bracket 107 will rest upon the edge of the sheet at the rear of the slot 98 and will yieldably hold the sheet so that 80 as the upward movement of the folder blade continues the edge of the sheet will be folded or doubled upon itself and moved past the lip 108 and carried into the bight of the folding rollers 97, as shown in Figure 8, whereby the 85 end edges of the several tongues will be doubled on themselves for a portion of their length. 90

Pivoted to and depending from the brackets 104 are links 117 which have their lower ends pivoted to crank arms or levers 118 extending upwardly and forwardly and secured to a rock shaft 119 journaled in suitable bearings secured upon the standards 2. Secured to the rock shaft 119 is a crank arm 120 which 105 extends forwardly to a point below the shaft 27 and is equipped with a roller 121 bearing against a cam 122 secured on said shaft so that as the high part of the cam rides upon the roller 121 the crank 120 will be 110 lowered and the levers 118 moved upwardly to carry the folder blade 100 into the folding position. In order that the blade may not be moved upwardly to such an extent that it 115 would be gripped by the rollers 97, a stop member 123 is secured to the end of the crank 120 and is slotted so that it may pass the shaft 27, as will be understood upon reference to Figure 3. When the crank 120 is 120 swung downwardly, the stop member 123 will, of course, follow the movement and the upper end of the slot or opening therein will 125 eventually be brought into contact with the shaft 27 so that the blade cannot move into binding relation with the rollers 97. The 130

crank 120 is, of course, so mounted upon the rock shaft 119 that it may have some lost motion thereon under the influence of the cam 122 if said cam should continue to act on the roller 121 when the stop member 123 is in contact with the shaft 27 but under normal conditions the frictional engagement of the crank with the shaft 119 will transmit the movement of the crank to the shaft. To maintain the engagement of the roller 121 with the cam 122, a tension spring 124 is provided about the shaft 119 having one end engaged with the crank and its other end engaged with an adjacent frame member.

The action of the folding mechanism is so timed relative to the action of the cutters that two sheets or leaves will be brought into position for folding before the folder blade moves upwardly. This feature of the machine is desirable because the tongues on adjacent leaves are staggered and the tongues on one leaf fit within the spaces between the tongues on another leaf and by folding two leaves simultaneously the relation of the tongues is established and they are so presented to the glue-applying elements that the glue will be applied through the full width of the leaf at each operation. It is essential that the leaves be properly aligned when presented to the folder mechanism and there are, therefore, provided jogger devices mounted upon the table 82. The table 82 has a central longitudinal plate 125 set therein and in one side edge of the table 82 is a longitudinally extending recess 126. The plate 125 has a longitudinal slot 127 formed therein, the walls of the slot being rabbeted, as shown at 128 in Figure 5, and carried by said rabbeted walls is a slide 129 to the upper side of which is secured a plate 130 which serves as a cover for the slot and rests upon the plate 125 to aid in supporting the slide. Secured to the upper end of the slide 129 and projecting transversely thereof to play over the table 82 is a jogger bar 131, from the upper edge of which a cover and guide plate 132 extends at an angle to the top of the table so as to meet the table and form a skid over which the advancing sheets may pass. The sheets, of course, will drop onto the table at the rear of the jogger bar 131 and said bar is reciprocated so that the sheets will be pushed rearwardly to come to rest against the stop bar 92, and it may be noted at this point that the rear edge of the slotted bar 91 is longitudinally recessed, as shown at 133 in Figure 6, to accommodate said stop bar and permit the lip 108 to extend the full length of the rollers 97. To effect the desired jogging reciprocatory motion of the bar 131, a link 134 is provided below the table and the plate 125 and has its front end pivoted to the under side of the slide 129 while its rear end is pivoted to the inner end of a bell crank 135 which is fulcrumed on

the under side of the plate 125. The outer end of the bell crank is pivotally attached to a pitman 136 slidably mounted in the frame bar 84, as indicated at 137, and having its outer end projecting through the frame bar 84 to be operatively engaged with the rocking arm 138. Said rocking arm 138 extends forwardly and is secured to a rock shaft 139, mounted vertically upon the adjacent standard 2, and at the lower end of said shaft 139 is secured a crank or rocking arm 140 which extends forwardly and is equipped at its forward end with a roller 141 bearing against a cam 142 which is secured upon a transverse shaft geared to the motor. As the shaft rotates, the crank 140 will, of course, be rocked in a horizontal plane and this movement will be transmitted through the shaft 139 to rock the arm 138. When the high part of the cam 142 acts to rock the arm 140, the arm 138 will push the pitman 136 inwardly and the bell crank 135 will be, consequently, rocked to pull the jogger bar 131 rearward and cause the end of the sheet to rest squarely against the stop bar 92. As the low part of the cam reaches the roller 141, an expansion spring 143, arranged between the rocking arm 138 and the frame member 84, will expand and rock the arm in the reverse direction so that the jogger bar will be moved upwardly upon the table 82. Carried by the pitman 136 to play within the recess 126 of the table is a jogger rail or board 144 which extends longitudinally of the table and has its forward end turned outwardly, as shown at 145, while at the opposite side of the table is a fixed rail 146. When the pitman 136 is reciprocated, the jogger board or rail 144 will, of course, move therewith and it will impinge against the side edge of the sheet presented thereto and move the sheet over to bear against the fixed rail 146 so that the sheets will be positively aligned and will be superposed in registration over the folder blade. The fixed rail 146 has its forward end curved outwardly, as shown at 147, and aligned with the outer side of the recess 126 is a similar rail 148 so that the sheets coming from the feed rollers 85 and 86 will be properly guided onto the table 82, and it will be noted, upon reference to Figure 3, that the ends of the guide rails 146 and 148 are tapered so that they will enter the bight between the feed rolls. The table 82 is preferably composed of a plurality of parallel longitudinal abutting boards or strips of material, as will be understood upon reference to Figures 4 and 5. These strips and the guide rails are carried by cross rods 400 secured in the frame bars 84, brackets 401 being secured to the under sides of the strips and adjustably mounted on the cross rods and the jogger rail 144 being secured upon the pitman in a similar manner. Preferably,

as indicated in Figure 3, the brackets 401 are of such form as to be easily engaged with or removed from the cross rods so that more or less table strips may be used as desired and 5 the chute thereby adjusted to accommodate wider or narrower sheets.

The sheets with their folded edges pass upwardly between the rollers 97 which press the plies of the folds together and direct the 10 sheets upwardly between guide plates 149 and 150 which are of arcuate form and converge toward their upper rear ends, and it may be noted at this point that the upper edge of the folder blade is preferably constructed with teeth so that it will more effectively engage the notched end portions of the leaves. The guide plates 149 and 150 are supported by brackets 151 and 152, respectively, secured conveniently upon the 15 supporting frame structure, and the upper rear or delivery ends of these plates are arranged at the right defined by rollers 153 arranged one above the other and serving to press the folds of the sheets and feed the 20 sheets to the glue-applying devices.

A shaft 77, mounted on the lower portion of the frame, is driven by a belt 78 directly from the motor 7, said belt being trained about a pulley 79 on the shaft 77. A chain 30 241 is trained about a sprocket on the shaft 77 and about a sprocket 240 on a shaft 239 mounted on the upper part of the frame. The shaft 239 is also equipped with a gear 238 which meshes with a gear 243 on the lower roller 153 so that said rollers will be positively rotated. The gear 238 also meshes with one of the gears 244 on the rollers 97 so that said rollers will also be positively rotated, and the shaft of the lower 35 roller 97 carries a sprocket 245, a chain 246 being trained about said sprocket and a sprocket 247 at the end of the feed roller 85 so that the latter will be positively driven.

The cut sheets pass from the cutting mechanism onto the table 82 and thence to the reciprocating folder blade. Two sheets have the free ends or tips of their tongues folded and, simultaneously with the folding action, are caused to advance somewhat toward the glue-applying devices, indicated at 300. The rollers 97 flatten the folds slightly but do not crimp them to the desired extent, and the crimping is accomplished by the rollers 153 which also feed the sheets toward the glue-applying devices.

Having thus described the invention, what is claimed is:

1. In a book-making machine, the combination of a chute receiving sheets to be bound, feed rollers to feed the sheets into the chute, folder mechanism at the lower end of the chute and resilient guards extending longitudinally above the chute in the path of the advancing sheets from a point adjacent the feed rollers.

2. In a book-making machine, the combination of a chute receiving sheets to be bound, a folder mechanism at the lower end of the chute, and means in the chute for alining the ends and sides of the sheets passing therethrough. 70

3. In a book-making machine, the combination of a chute receiving the sheets to be bound, a folder mechanism at the lower end of the chute, a fixed rail at one side of the chute and a laterally shiftable jogger rail mounted at the opposite side of the chute to aline the sheets passing therethrough. 75

4. In a book-making machine, the combination of a chute receiving sheets to be bound, a folder mechanism at the lower end of the chute, and a longitudinally movable jogger at the receiving end of the chute acting upon the sheets to aline their advancing edges at the folder mechanism. 80

5. In a book-making machine, the combination of a folder mechanism, means for feeding sheets to the folder mechanism, said folder mechanism comprising a stop bar normally disposed in the path of the advancing sheets, a folder blade movable upwardly against the sheets adjacent the stop bar and an element carried by the stop bar and movable to yieldably engage the ends of the sheets whereby the upward movement of the folder blade 95 will produce a fold in the end portions of the sheets. 90

6. In a book-making machine, the combination of a folder mechanism, and means for feeding sheets to the folder mechanism, said folder mechanism including a pair of cooperating rollers, a sheet-engaging element below the rollers movable toward and from the same and a blade movable to and from the rollers past said element whereby to present 105 the ends of the sheets to the rollers and produce a fold therein.

7. In a book-making machine, the combination of a folder mechanism, means for feeding sheets to the folder mechanism, said 110 folder mechanism including a pair of cooperating rollers, and a blade movable to and from the rollers whereby to present the ends of the sheets to the rollers and produce a fold therein, and means for limiting the 115 movement of the folder blade toward the rollers.

8. In a book-making machine, the combination of a folder mechanism, and means for feeding sheets to the folder mechanism, said 120 folder mechanism comprising elements to restrain upward movement of the ends of the sheets, and a folder blade movable upwardly between said elements whereby to feed the ends of the sheets between the said elements 125 and produce a fold therein.

9. In a book-making machine, the combination of a folder mechanism, and means for feeding sheets to the folder mechanism, said folder mechanism including a slotted sheet- 130

supporting bar, a folder blade movable through said bar to engage a sheet over the slot therein, a movable stop bar adjacent said slotted bar to arrest the sheets thereover, a bracket projecting from said stop bar over the slotted bar, and means whereby said bracket will be caused to yieldably hold sheets to the slotted bar whereby the engagement of the blade with the sheets will form 10 a fold therein.

10. In a book-making machine, the combination of a chute through which sheets to be bound may pass, a skid in the chute at the receiving end thereof, a folder mechanism 15 at the lower end of the chute, a stop bar adjacent the folder mechanism, a jogger bar disposed transversely in the chute adjacent the skid and means for reciprocating said jogger bar longitudinally of the chute 20 whereby to align sheets against the stop bar.

11. In a book-making machine the combination of a chute through which sheets to be bound may pass, a folder mechanism at the lower end of the chute, a fixed rail at one 25 side of the chute, a jogger rail at the opposite side of the chute, a transverse stop bar in the upper end portion of the chute, an angle lever mounted on the chute, operative connections between said lever and the jogger bar, a pitman connected with the lever and the jogger rail, and means for reciprocating 30 the pitman.

12. In a book-making machine, the combination of a chute having a transverse slot 35 at its lower end, means for stopping a sheet with its end over said slot, leaf-restraining elements above and at opposite sides of said slot, and a folder blade movable upward through the slot to engage a sheet and push 40 it between said elements to fold the sheet.

13. In a book-making machine, the combination of a chute having a transverse slot at its lower end, a pair of folder rolls above the slot, a stop bar in the path of sheets moving 45 from the slot, a bracket on said bar overhanging the end of the chute and having an upwardly projecting lip extending between the rolls, a deflector at the opposite sides of the slot between the slot and the rolls, a 50 folder blade movable through the slot and between the bracket and the deflector to engage a sheet and form a fold therein, and means for moving the stop bar and bracket simultaneously with the blade whereby a 55 sheet may be held over the slot to be engaged by the blade and released as the blade moves upwardly.

14. In a book-making machine, the combination of a chute having a transverse slot 60 at its lower end, a folder blade movable through the slot, a stop bar in the path of a sheet moving over the slot, a bracket on the stop bar overhanging the end of the 65 chute, means for reciprocating the folder

blade, a rocking lever fulcrumed between its ends below the chute and having one end under the blade to move therewith, a link connecting the opposite end of the lever with the stop bar, and a retractile spring at its upper end connected with the stop bar and its lower end secured at a fixed point.

In testimony whereof I affix my signature.
CHARLES C. HOWARD. [L.S.]
